UNITED STATES PATENT OFFICE.

ROBERT MILLS BALENTINE, OF GREENVILLE, SOUTH CAROLINA.

PILLOW-SHAM HOLDER.

No. 806,766.

Specification of Letters Patent.

Patented Dec. 12, 1905.

Application filed June 23, 1905. Serial No. 266,637.

To all whom it may concern:

Be it known that I, ROBERT MILLS BALENTINE, a citizen of the United States of America, and a resident of Greenville, county of 5 Greenville, State of South Carolina, have invented certain new and useful Improvements in Pillow-Sham Holders, of which the following is a full and clear specification, reference being had to the accompanying drawings, in 10 which—

Figure 1 is a perspective view of a bedstead provided with my invention. Fig. 2 is a side elevation of the head portion thereof. Fig. 3 is a rear view of the head portion of 15 the bed, partly broken away for compactness. Fig. 4 is a detailed vertical section showing more clearly the means for vertically adjusting the device; Fig. 5, a detailed perspective view of the same devices separated 20 for the purposes of better illustration, and Fig. 6 a detailed perspective of one of the springs employed for holding the operating-shaft in its bearings.

The object of this invention is to provide 25 simple mechanism for holding and adjusting the sham-supporting bar, which mechanism shall be practically hidden behind the headboard of the bed and shall be capable of attachment to the rear side of the headboard, 30 where it will not mar the face of the headboard.

To the accomplishment of these objects and such others as may hereinafter appear the invention consists of the parts and combination of parts hereinafter fully described, 35 and particularly pointed out in the appended claims, reference being had to the accompanying drawings, forming a part of this specification, in which the same reference characters designate like parts throughout the several views.

In the drawings, A designates a headboard, to the rear face of each corner-post of which is attached a vertical supporting-way B, 45 which is provided with rearward-extending vertical flanges b and screw-holes b² at its ends, said flanges b being enlarged at b¹ for the purpose of forming bearings for the shaft E, these bearings being slotted, so that the 50 shaft may be readily placed in the bearings and removed therefrom. Flat springs F, attached at their lower ends to the rear face of the headboard by screws and blocks f, serve to normally and removably hold this shaft in its bearings. This shaft extends entirely 55 across the rear face of the headboard and is

provided with a milled operating-wheel e' at one end and between each pair of ears b' with an elastic friction-wheel e.

The friction-wheels e each bears resiliently 60 upon the transversely-serrated face c of a vertical bar C, this bar lying and fitting within the way formed between the vertical flanges b on each of the supporting-bars.

Attached to the outer side edge of each bar 65 C at the upper end thereof is a bracket-arm c', which extends forward to a point in front of the headboard and has its extremity bent upward to engage in a hole d², formed in the adjacent end of a bar D, which bar extends 70 across in front of the headboard and is provided with the sharp pins d to engage and support the shams S. The lower end of each bar C is enlarged at c² to prevent the bar from being raised high enough to slip from under 75 the elastic friction-wheel.

It will be observed that by simply turning the shaft E by the thumb-wheel e' the sham-carrying bar may be raised or lowered. It will be observed that all the mechanism for 80 raising and lowering the sham-holder is located on the rear face of the headboard, where it will be out of the way, and it will be seen also that this mechanism is of such a character that it will not be readily injured by being 85 jammed against the wall. It will be seen also that the mechanism I employ is very simple and inexpensive in construction and that it may be applied to any bedstead and that its application to the bedstead will not 90 in the least mar the front of the headboard.

Having thus fully described my invention, what I desire to secure by Letters Patent is—

1. In combination with a bedstead, a pair of vertical ways attached to the rear side of 95 the headboard thereof, a vertically-movable bar arranged to slide in each of these ways, means for raising and lowering said bars, bracket-arms carried by said bars and extending around to a point in front of the 100 headboard, and a sham-carrying bar supported on these bracket-arms, substantially as set forth.

2. In combination with a bedstead, of a sham-holding bar extending across in front 105 of the headboard thereof, a bracket-arm engaging each end of said bar and extending around behind the headboard, and means for supporting and raising and lowering said bracket-arms, said means being supported 110 on the rear face of the headboard.

3. In combination with a bedstead, of a

sham-holding bar extending across the front of the headboard thereof, bracket-arms attached to this bar and extending around behind the headboard, a vertically-slidable bar attached to the rear end of each bracket-arm, and means supported on the rear face of the headboard for simultaneously raising and lowering said bars, substantially as set forth.

In testimony whereof I hereunto affix my signature, in the presence of two witnesses, to this 22d day of June, 1905.

ROBERT MILLS BALENTINE.
